UNITED STATES PATENT OFFICE.

VICTOR H. SLINACK, OF PHILADELPHIA, PENNSYLVANIA, ASSIGNOR TO PENNSYLVANIA GLOBE COMPANY, OF PHILADELPHIA, PENNSYLVANIA, A CORPORATION OF PENNSYLVANIA.

INVERTED INCANDESCENT LIGHT.

Application filed April 27, 1921. Serial No. 464,929.

To all whom it may concern:

Be it known that I, VICTOR H. SLINACK, a citizen of the United States, residing at Philadelphia, in the county of Philadelphia and State of Pennsylvania, have invented a new and useful Improvement in Inverted Incandescent Lights, of which the following is a specification.

The principal objects of the present invention are to provide an inverted incandescent light which will give good candle power and avoid flash-backs when operated with a relatively large supply of air to the mixture, even in connection with such gas as is now supplied in many cities; to provide for satisfactorily lighting inverted incandescent lights from pilot lights; and, in general, to improve the efficiency and broaden the application of inverted incandescent lights. Other objects of the invention will appear from the following description and the invention itself will be claimed at the end hereof. In the description reference will be made to the accompanying drawings forming part hereof and illustrating features of the invention and in which

Figure 1 is a view, principally in central section, and showing so much of an inverted incandescent light as is necessary for an understanding of the invention, and

Fig. 2 is a similar view illustrating features of the invention.

In the drawings 1 is an inverted burner shown as consisting of refractory material and as having a cylindrical internal wall 2. 3 is a tube from which the burner 1 depends by means of the screw thread connection 4, and through which a mixture of air and gas is supplied as is well understood. 5 is an inverted incandescent mantle arranged beneath the burner 1 and supported from some convenient part of the fixture 6 as by means of a spider 7 which provides egress for the products of combustion. 8 is a core projecting into the bore of the burner 1 and having a wall 9 which confronts and is spaced from the internal wall 2 of the burner to provide between said walls an annular discharge duct. The core 8 is shown as of generally cylindrical form with flat ends although, more accurately, it is of the form of a frustum of a cone. Lava is a good material from which to make the core. The lower ends of the core and of

the burner 1 are shown as arranged in alignment. 10 is an axial pit in the lower end of the core and as shown in Fig. 1, it does not extend through the core but, as shown in Fig. 2, the pit 10^a extends through the core and communicates with the pilot light tube 11. The pilot light tube 11 when of the inverted U-form shown, and arranged through the wall of the tube 3, affords one means for supporting the core. Another means for supporting the core comprises a rod 12 depending from arms 13 carried by a ring 14 arranged in the top of the burner. This rod 12 is guided centrally of the bore of the burner by radial arms 15.

In use the comparatively elongated annular discharge duct or passage between the walls 9 and 2 discharges the mixture of air and gas into the mantle 5 in such a way that the heating flame is appropriately directed and applied to the surface of the mantle for heating it to brilliant incandescence and giving good candle power, and the products of combustion escape upward past the arms 7 and into and through the fixture 6 without unduly retarding the descent of the flame by needlessly crossing it. It may be remarked that there is formed in the flame a cone with its apex substantially at the pit 10 or 10^a, which cone is of greenish color and indicates that the character and distribution of the heating flame is as it should be. When the heads of the core are flat they do not direct the combustible mixture unduly towards the walls 2 and hence the mixture escapes from the burner with proper velocity and pressure. By arranging the pilot light inside of the mantle a comparatively strong pilot flame can be maintained without danger of blackening the mantle.

Moreover the mantle protects the pilot light from drafts which might otherwise blow it out. Again the effects of the explosions which take place when the burner is lighted and extinguished are not felt near or directly under the burner tube in anything like the degree that they are felt in the space between the burner tube and the mantle ring and fixture so that the pilot light is not extinguished thereby. The fact that the pilot light is located near the outlet of the burner tube diminishes the force of such explosions because there is formed

- less volume of explosive mixture, and in this way the life of the mantle is prolonged. The location of the pilot light inside of the mantle and close to the burner tube insures 5 its relighting when the main burner is being extinguished and insures its lighting the main burner when the pilot light is being extinguished and it is desirable that the pilot light be extinguished while the main 10 burner is burning because the heat of the main burner, heating the gas within the pilot tube, causes the pilot tube to coke up with carbon and the like.

It will be obvious to those skilled in the 15 art to which the invention relates that modifications may be made in details of construction and arrangement without departing from the spirit of the invention which is not limited as to those matters or otherwise than as the prior art and the appended 20 claims may require.

I claim:

1. An inverted incandescent light comprising an inverted burner having a portion 25 of its bore in the form of an upright cylinder, a fixed cylindrical core impene-

trable by the mixture and arranged in and confined to the upright cylindrical portion of the bore of the burner and providing between confronting walls of the cylindrical portion of the burner and of the core an elongated upright annular cylindrical discharge duct of substantially constant cross section and co-axial with the core and with the cylindrical portion of the burner. 30

2. An inverted incandescent light comprising an inverted burner having a portion 35 of its bore in the form of an upright cylinder, a fixed cylindrical core impene- trable by the mixture and arranged in and confined to the upright cylindrical portion of the bore of the burner and providing between confronting walls of the cylindrical portion of the burner and of the core an elongated upright annular cylindrical discharge duct of substantially constant cross section and coaxial with the core and with the cylindrical portion of the burner, and said core having flat heads of which one is aligned with the outlet end of the burner 40 and is provided centrally with a pit. 45

VICTOR H. SLINACK.
